CLAIM

The ornamental design for an intervertebral implant, as shown and described.

DESCRIPTION

FIG. 1 shows a perspective view of the top surface of the intervertebral implant showing a new design.

FIG. 2 shows a top view thereof;

FIG. 3 shows a perspective view of the bottom surface thereof;

FIG. 4 shows a front view thereof;

FIG. 5 shows a rear view thereof;

FIG. 6 shows a side view thereof; and,

FIG. 7 shows another side view thereof.

In the above drawings the broken lines and the areas within the broken lines form no part of the claimed design.
